INTERRUPTER FOR HIGH CURRENT INTENSITY

Louis Debuit, Grenoble, France, assignor to Etablissements Merlin & Gerin, Grenoble, France

Application April 1, 1954, Serial No. 420,374

Claims priority, application France April 14, 1953

11 Claims. (Cl. 200—146)

The invention relates to an interrupter for high current intensity and more particularly to an interrupter in which for each pole of the interrupter there is provided a pair of stationary contacts to be electrically connected by a bridging contact member.

Particularly, it is an object of the invention to develop an interrupter of the aforesaid type of small space requirement which, however, simply by modification of a single dimension, viz. the width, may be adapted to a great range of current intensities, while the other dimensions of the apparatus, height and depth, remain unchanged.

It is a further object of the invention to arrange for such a modification of the width of the apparatus for adapting it to various ranges of current interrupting capacity simply by varying the number of certain contact units, particularly of the contact members which bridge the main contacts or the arcing contacts, or both.

A still further object of the invention is a development of a bridging contact member, hereinafter shortly designated as "contact bridge", such that at each pole to be interrupted, the circuit, through the lifting of the contact bridge from the stationary contacts, is doubly broken, and the arc thus rapidly extinguished.

It is a further object of the invention to provide for the contact bridge an actuating mechanism which is to start the opening motion with a shock so as to counteract any effects of an accidental prior welding of the stationary and mobile contacts.

These and other objects of the invention will be achieved when, in accordance with the invention, in current interrupters with a pair of stationary contacts for each pole to be interrupted, the contact bridge comprises at least one rotary contact member or one or more units, each unit of one or more rotary contact members. This rotary contact member or the units of rotary contact members thus constitute a movable bridge which by means of an actuating mechanism may be moved into or out of the bridging, contact making position between the stationary contacts.

These contact bridges comprising one or more contact members or rollers shaped as bodies of revolution, such as cylinders, rollers or rings, and which as a rule are rotary, will be arranged to bridge the stationary main contacts themselves and further contact bridges with one or more such contact members will be arranged to bridge the arc horns or runners with which the main contacts may be provided.

In this case, a primary contact bridge of one or more units, each unit of one or more rotary contact members, will serve for bridging the main contacts directly and thus as main movable contact of the interrupter whereas a secondary contact bridge comprising one or more rotary contact members each, will serve as movable arcing contact and bridge the arc horns, with its axis of rotation spaced from and parallel to the bridging of the

2

main contacts through the primary contact bridge and to the axis of rotation of its contact members.

In a further development of the invention, the actuating mechanism of the interrupter includes driving members, and connecting members between both contact bridges for moving by means of the connecting members both contact bridges concurrently into the circuit making or the circuit breaking position, into or out of the bridging, contact making position between the contact pieces and between the arc horns, respectively. Retarding mechanisms are interposed between the connecting members and the rotary contact members of both contact bridges for delaying the circuit breaking through the secondary or arcing contact bridge relatively to the circuit breaking through the primary contact bridge, retarding mechanisms which may also delay the circuit making of the primary contact bridge relatively to the circuit making of the secondary, arcing contact bridge.

Thus, while the movements of both axes which carry the principal and the arcing contact bridges are coupled, the arcing rotary contact members, when the interrupter is to be opened, are separated from the arc horns only after the primary rotary contact members had been separated from the stationary main contacts and, conversely, are closed first.

For thus delaying the action of the one contact bridge relatively to the other, in accordance with this development of the invention, the motion transmitting members which couple the driving members of the actuating mechanism with the rotary contact members of the contact bridges provide for an idle path between the driving members and the rotary contact member or members of the secondary contact bridge. Such an idle path, but of shorter length, is also provided between the driving members and the rotary contact member or members of the primary contact bridge.

This idle path makes it possible, during the movement of the motion transmitting members on this path, to accelerate the driving members to a velocity such that they strike on the contact bridge or bridges in a shock movement and thus lift abruptly the rotary contact member or members from contact with the stationary contacts.

Through this opening of the contacts under a shock, the effects of an accidental welding of the stationary and mobile contacts are eliminated.

The invention further provides for a mounting of the rotary contact members on their supporting shaft or axle which makes unnecessary any particular regulating of the setting of the contacts.

The interrupter, furthermore, through the employ of rotary contact members, such as rollers or revolvable rings, is rendered remarkably insensitive to deposits which might settle between the stationary and the mobile contacts when the atmosphere surrounding the interrupter is contaminated.

Since from their contact making position, where they bridge a pair of stationary contacts, the rotary contact members are lifted in the direction towards which the arc develops, the arched sectors of the rotary contact members in contact with the stationary main contacts or with the arc horns are particularly suited for the development of the arcs since for the current to be interrupted an arc is drawn at two places, i. e. at both sides of each rotary contact member.

Furthermore, since there are no movable parts to be conductively connected with the incoming and outgoing leads, no conductor strands are needed. A possible source of defects and disturbances thus is eliminated and the structure simplified.

The above and other features and objects of the in-

vention and its nature will become apparent as the now ensuing specific description of the invention proceeds in which the invention will be described with reference to the accompanying drawings which form part of this specification and which by way of example illustrate an embodiment of the invention and a modification thereof. It will be readily understood, however, that these drawings are intended to be explicative of the invention but not limitative of its scope and that the invention may be embodied in other forms without departing from the principle underlying my invention and the ambit of my appended claims.

In the drawings:

Fig. 1 is a schematic elevational side view, partly in section along line 1—1 of Fig. 2, of a pole of an interrupter of the invention, the rotary contact members of the stationary main contacts and of the arc horns being in bridging, circuit making position;

Fig. 2 is a schematic elevational section along line 2—2 of Fig. 1 and partly a front view of the interrupter;

Figs. 3 and 4 respectively are, on an enlarged scale, sections along line 3—3 of Fig. 4 and line 4—4 of Fig. 3, of a rotary contact member of the main contacts in closed, or bridging, position;

Fig. 5 is a view similar to that of Fig. 1 which however shows the rotary contact members both of the main contacts and of the arcing contacts in open, circuit-breaking position;

Figs. 6 and 7 respectively are, on an enlarged scale, sections along line 6—6 of Fig. 7 and line 7—7 of Fig. 6 showing, similar to Figs. 3 and 4, a rotary contact member in open, circuit breaking position;

Figs. 8, 9 and 10 respectively are a front, a side view, and a top view, on an enlarged scale, of a connecting member provided between both contact bridges; and

Fig. 11, similar to Fig. 2, is a schematic elevational front view, partly in section corresponding to the section line 11—11 of Fig. 1, of an embodiment in which the interrupter pole is composed of two stationary and mobile contact units aligned in the width direction.

In the embodiments of Figs. 1 to 10, the stationary main contacts are designated by 11 and 12. These two contacts are arranged symmetrically at a certain distance from the median symmetry plane of the apparatus when seen as illustrated in Figs. 1 and 5. In the modification of Fig. 11, the visible main contacts are designated by 41, 43, the complementary contact pieces are 42, 44, written in brackets since not visible on the figure.

These stationary main contacts are supported upon the bars 13, 14, 15, 16, which form part of the framework of the apparatus, which framework, however, since it forms no part of the invention is not shown here, as are not, for the same reason, the means for securing the parts at the framework. These bars, for apparatus of lower current intensity, are of insulating material whereas, for apparatus of higher current intensity, metal bars may be employed which are coated with insulating material as indicated at 17 in Fig. 1. For securing the contact pieces 11, 12, against lateral displacement, they may be held in position at both their sides by rings of square form secured by screws to the bars. These square rings or perforated, square members embracing the bars are not shown here in order not to crowd the representation.

The incoming and outgoing leads are respectively designated by 19 and 20. Each stationary main contact carries at its top an arcing horn or arc runner 21, 22, Figs. 1, 2 and 5, and 23, 24, 25, 26 in Fig. 11. In this figure, the numerals 25, 26 are in brackets, they designate the opposite pair of arcing horns not visible in this figure. The arcing horns are disposed between walls 31, 32, 33, 34, of refractory material of an arcing chamber and are secured by conventional means, here not shown, to the frame bars 13 and 15. The rotary contact members or rollers, 36, Figs. 1 to 7, and 37, 38, Fig. 11, are

here in the form of rings which, together with their shafts 39, 40, respectively, about which they are revolvable, form the main or primary contact bridge. This primary contact bridge in its circuit making or closed position 5 bridges the main contacts 11, 12, directly and thus closes the current on the main circuit 19—11—36—12—20. When raised out of their closing or bridging position, these contact rollers, 36, break the circuit through the main contacts 11, 12, and the primary contact bridge constituted by the contact rollers or rings 36. Similarly, in the embodiment of Fig. 11, where the main contacts 41, 43 are connected to the one lead of the network and the main contacts 42, 44 to the other lead, the circuit through the main contacts will be broken through the lifting of the contact rings 37, 38 from the main contacts 41, 42 and 43, 44, respectively.

The rings 36 may be of any number, for instance five as shown in the embodiment of Figs. 1 to 7, or they may be arranged in several sets of any number of rings such as in two sets 37, 38, each of five rings as shown in Fig. 11. Ever according to the intensity range of the current to be broken, any other number of rollers or roller units may be employed, each unit of any desired number of rollers or rings, corresponding to the current breaking capacity, for which the circuit breaker is designed;

The rings are strung on their shafts, 39, 40, loosely, so that they may revolve thereabout. The shaft 39 or 40 of the contact bridge is operated by connecting members or bars, two of them, 55, 56, in the embodiment of Figs. 1 to 10, and three in the embodiment of Fig. 11, one bar, 57, 59, on each side of the contact bridge, and one, 58, in the midst. These bars thus serve as members for transmitting the motion from the actuating mechanism to the contact bridges. The actuating mechanism of the 30 interrupter further comprises the actuating shaft 61 which may be rocked by any conventional or convenient means, by hand or remote control, here not shown. Shaft 61 further carries for each connecting bar a pinion 62 which engages a toothed rack, 63, of metal, secured 35 by screws, rivets or otherwise, as indicated at 64, Fig. 1, to the connecting bars 55, 56, or 57, 58, 59. Shaft 61 when rocked in the opening sense, counter-clockwise in the sense of Fig. 1, will thus lift, by means of the pinions 62 and racks 63, the connecting bars 55, 56, or 40 57, 58, 59, into the position shown in Fig. 5 and on reverse motion lower them into the position of Figs. 1 and 2, or 11.

In order to provide an idle path between the motion transmitting elements and the contact bridges which they 45 actuate, shaft 39 inside the rings 36, and also inside the rings 37, 38, is shaped with a throat 46 and is thus flattened. On operation of the actuating means, during the motion of the transmitting elements or connecting bars 55, 56, or 57, 58, 59 the motion of the actuating means, and particularly of shaft 39 or 40, may thus be accelerated to great velocity before the rings 36, or 37, 38, are lifted out of the bridging position between the stationary main contacts 11, 12, or 41, 42, 43, 44. The shaft 39 or 40 will thus strike in a shock movement on the bridging contact rollers or rings 36, or 37, 38, and lift them abruptly from the stationary main contacts, and thus eliminate the effects of any prior accidental welding of the contacts.

Throat 46 is shaped with a cylindrical bore 47, perpendicular to, or in the diametrical direction of, each ring 36, 37, 38. This bore 47 houses a spring 48 which bears upon a ball 49 whose diameter corresponds to that of the bore. Ball 49, thus urged by spring 48 against ring 36, or 37, 38, engages and guides the ring by means of a circular groove 50 in the inside circumference of the ring and urges the ring towards the contact making position.

The contour of the throat is composed of two sectors, a lower one, 51, housing the spring and ball and of a radius, smaller or slightly smaller than that of the inner circumference of the ring, and an upper sector, 52, of the same

radius as the inner circumference of the ring but with the center axis displaced between the center axis of the lower sector and the diametrically opposed side or underside of the throat. Thus, in the closed, bridging position, shaft 39 or 40 itself with the lower sector 51 of its throat 46 does not contact the rings but presses them by means of the springs 48 and balls 49 and causes the rings to bear against the stationary contact pieces 11, 12, or 41, 42; 43, 44. Through this provision of the throat, the free space *b*, Fig. 3, or an idle path is provided at the upper side of shaft 39, or 40, between the upper sectors 52 and the inside circumferences of the rings 36, or 37, 38, when the rings are in the closed or contact bridging position, Figs. 3 and 4. Conversely, in the open position of the contact bridge, the upper sector 52 of throat 46 will bear with its whole surface against the inner circumference of the rings, Figs. 6 and 7.

The mobile arcing contact bridge, in the embodiments illustrated, comprises for each pair of arc horns 21, 22; and 23, 25; 24, 26, a single roller 66 and 67, 68 rotatable about or with its shaft 69 and 70, respectively. These shafts are mounted, vertically slidable with their journals 71, 72; and 73, 74, 75, in slots 76 of the connecting bars 55, 56 and 57, 58, 59, respectively. Correspondingly slotted caps or sockets 77 are inserted into the upper ends of bars 55, 56; 57, 58, 59 and are secured therein by means of screws, as indicated at 78. These caps 77 house springs 79 which urge shafts 69, 70 and thus rollers 66; 67, 68, downwards, towards the bridging, circuit closing position.

The connecting bars 55, 56, Figs. 1 to 10, and 57, 58, 59, Fig. 11, are of electrically insulating material while the racks 63 and the caps or sockets 77 housing the springs are of metal.

The slots 76 are so disposed in the connecting bars 55, 56 and 57, 58, 59 relatively to the shafts 69 and 70, respectively, and are of such a length that the actuating mechanisms together with the connecting bars may idly move along an idle path of a length *a*, Fig. 2, relatively to the shafts 69 or 70 and the arcing rollers 66 or 67, 68 before the connecting bars at the ends of the slots strike against the shafts and raise the roller 66 or the rollers 67, 68 out of contact with the arc horns 21, 22, or 23, 25; 24, 26, respectively, for the purposes set forth hereinabove.

The operation of the device is as follows:

When the interrupter, for instance the interrupter illustrated by Figs. 1 to 10, is in the closed position, the springs 48 of the rings 36 on shaft 39 and the springs 79 of the connecting bars 55, 56 are compressed. The springs 48 by means of the balls 49 press the rings 36 against the contact pieces 11, 12 and the springs 79 bias the arcing roller 66 against the arc horns 21, 22. When the interrupter is to be opened, actuation shaft 61 is rocked, counter-clockwise as seen in Fig. 1. The pinions 62 by driving the racks 63 move both bars 55, 56 upwards, raising with them shaft 39. During the first part of the course of shaft 39, along the idle path *b*, or the clearance provided through the throat 46 of shaft 39 between shaft 39 and the rings 36, springs 48 will be released and will expand while by means of the balls 49 they still hold the rings 36 against the main contacts 11, 12. Only when shaft 39 has been raised through the idle path *b*, will shaft 39 strike the contact rings 36 and abruptly separate them from the main contacts 11, 12 and thus accomplish the first phase of the opening cycle of the interrupter. At this instant the circuit of the current is as follows:

Incoming lead 19—main contact 11—arc horn 21—arching contact roller 66—arc horn 22—main contact 12—outgoing lead 20.

During the upward motion of the connecting bars 55, 56 along the idle path or distance *b*, the springs 79 of the secondary contact bridge will be released and will expand while they still hold roller 66 biased against the arcing contacts 21, 22. The slots 76 are of a length to

make possible upward movement of the connecting bars 55, 56, without striking the journals 71, 72 of shaft 69 for a distance or an idle path *a*, Fig. 2, a distance which is somewhat greater than the distance *b*. Only after, during this upward motion, the connecting bars 55, 56 have traversed the idle path *a*, that is after the rings 36 have already been separated from the contact pieces 11, 12, will the connecting bars strike against the journals 71, 72, lift shaft 69 and will thus separate the arcing contact roller 66 from the arcing horns 21, 22 and thus completely and finally open the interrupter, Figs. 5 to 7. The springs 79 will then have expanded through the full length *a*.

At the separation of arcing roller 66 from the arc horns 21, 22, two current breaking arcs are developed, one between arc horn 21 and the one side of roller 66 and the other between arc horn 22 and the other side of roller 66. Both arcs will be extinguished in the arcing chamber formed by the walls 31, 32, 33, 34, be it exclusively through their natural expansion, be it by means of a magnetic blow field, not shown here.

Since the current is opened simultaneously at two points, the extinction of the arc is greatly facilitated. On the other hand, since shaft 39 strikes against the rings 36 only after the shaft has reached a certain velocity, the shaft strikes on the rings with a certain shock effect which will allow the rings to overcome the resistance which might be opposed to the separation of rings 36 from the contact pieces 11, 12 owing to a preceding accidental welding of rings and contact pieces. Similarly, the lifting of the arcing contact roller 66 from the arcing contacts 21, 22, is abrupt.

During the closing cycle, roller 66 will close the circuit first and only thereafter will the rollers 36 bridge the main contacts 11, 12.

By subdividing the pole of the interrupter into two contact pieces 11, 12, between which a mobile contact bridge constituted by the rollers 36 is inserted, the employ of wire strands becomes unnecessary and the construction is considerably simplified.

In the embodiment as illustrated in Figs. 1 to 10, the primary contact bridge comprises five rollers. It will be readily understood, however, that the number of the rollers may be any, varying in dependence upon the nominal intensity or current breaking capacity of the circuit breaker. Moreover, a standard unit for interrupting a certain nominal amperage may be established and the pole of the interrupter accordingly composed of an appropriate number of such standard units.

Fig. 11 as described hereinabove illustrates an embodiment where a pole of the interrupter is set up from two of such units. There are two sets of stationary contacts, one set comprising the contacts 41, 42, the other the contacts 43, 44. The contacts 41, 43 of one side of the pole are electrically connected to each other and to one of the leads whereas the contacts 42, 44, of the other side of the pole are also connected electrically to each other but are connected to the other lead. The apparatus further comprises two arcing rollers 67, 68, two sets 37, 38, of primary contact rollers, each set of five rollers, and three connecting bars, two, 57, 59, at the outside and one, 58, in the midst.

In the multipolar circuit breakers the primary and secondary contact bridges may be mounted upon and actuated by the same actuating shaft (61) with the obvious condition, of course, that the poles are electrically insulated from one another. The manufacture and holding in stock of the detached pieces of the circuit breaker will thus be greatly simplified, with the additional advantage that dependent upon the circuit breaking capacity of the circuit breaker only one dimension, viz. the width, is to be changed while the other dimensions may be the same.

I claim:

1. Current interrupter including a pair of stationary

main contacts for each pole to be interrupted; each of said main contacts being provided with an arc horn, a primary contact bridge comprising at least one contact member shaped as a body of revolution being associated with said main contacts for bridging the same directly; a secondary, arcing contact bridge comprising at least one contact member shaped as a body of revolution being associated with said arc horns for bridging the same parallel to the bridging of the main contacts through said primary contact bridge, both said contact bridges being disposed with their axes parallel to and at a distance from each other; and actuating mechanism for moving said contact bridges in predetermined sequence into and out of the bridging, contact making position between said main contacts and said arc horns.

2. Current interrupter including a pair of stationary main contacts for each pole to be interrupted; each of said main contacts being provided with an arc horn, a primary contact bridge comprising at least one rotary contact member being associated with said arc horns for bridging the same parallel to the bridging of the main contacts through said primary contact bridge, both said contact bridges being disposed with their axes parallel to and at a distance from each other; and actuating mechanism for moving said contact bridges in predetermined sequence into and out of the bridging, contact making position between said main contacts and said arc horns.

3. Current interrupter including a pair of stationary main contacts for each pole to be interrupted, a pair of arc horns provided at said main contacts, one horn at each main contact, a primary contact bridge comprising at least one rotary contact member being associated with said main contacts for bridging the same directly, a secondary, arcing contact bridge comprising at least one rotary contact member being associated with said arc horns for bridging the same parallel to the bridging of the main contacts through said primary contact bridge, both bridges being disposed with their axes parallel to each other, connecting members being provided between both said contact bridges, and actuating mechanism for moving, by means of said connecting members, both said contact bridges concurrently into circuit making and breaking positions, into and out of the bridging, contact making positions between said main contacts and said arc horns, respectively, retarding mechanism being interposed between said connecting members and the rotary contact members of both said contact bridges for delaying the circuit breaking through said secondary contact bridge relatively to the circuit breaking through said primary contact bridge.

4. Current interrupter including a pair of stationary main contacts for each pole to be interrupted, a pair of arc horns provided at said main contacts, one horn at each main contact, a primary contact bridge comprising at least one rotary contact member being associated with said main contacts for bridging the same directly, a secondary, arcing contact bridge comprising at least one rotary contact member being associated with said arc horns for bridging the same parallel to the bridging of the main contacts through said primary contact bridge, both said contact bridges being disposed with their axes parallel to each other, connecting members being provided between both said contact bridges and actuating mechanism for moving, by means of said connecting members, both said contact bridges concurrently into circuit making and breaking positions, into and out of the bridging, contact making positions between said contact pieces and said arc horns, respectively, retarding mechanism being interposed between said connecting members and the rotary contact members of both said contact bridges for delaying the circuit breaking of said secondary contact bridge relatively to the circuit breaking of said primary contact

bridge; said retarding mechanism being adapted for delaying the circuit making of said primary contact bridge relatively to the circuit making of the secondary contact bridge.

5. Current interrupter including a pair of stationary main contacts for each pole to be interrupted, a pair of arc horns provided at said main contacts, one horn at each main contact, a primary contact bridge comprising at least one rotary contact member associated with said main contacts for bridging the same directly, a secondary, arcing contact bridge comprising at least one rotary contact member associated with said arc horns for bridging the same parallel to the bridging of the main contacts through said primary contact bridge; actuating mechanism including driving members for operating the interrupter; connecting members being provided between both said contact bridges, said actuating mechanism for moving, by means of said connecting members, both said contact bridges concurrently into circuit making and breaking positions, into and out of the bridging, contact making positions between said main contacts and said arc horns, respectively; said actuating mechanism further including motion transmitting members coupling said connecting members with said contact bridges, said motion transmitting members providing for an idle path between said connecting members and each of said contact bridges; the idle path of the motion transmitting members provided at the secondary contact bridge being longer than the idle path of the motion transmitting members provided at the primary contact bridge; thereby, on actuation of said actuating mechanism for breaking the circuit, to allow, during the movement of said motion transmitting members along said idle paths, acceleration of said actuating mechanism to a velocity to strike in a shock movement the respective contact bridge, and further cause, first, abrupt raising of the rotary contact member from the main contacts and, timely delayed thereafter, the raising of the rotary contact member from the arc horns.

6. Current interrupter including a pair of stationary contacts for each pole to be interrupted and a contact bridge comprising at least one rotary contact member in form of a contact ring associated with said stationary contacts, and actuating mechanism including driving members and motion transmitting members coupling said driving members with said contact bridge; a shaft being provided and non-revolably connected to said actuating mechanism; said shaft carrying said contact ring freely revolvable thereabout; said shaft penetrating said ring with a throat, said throat housing a spring urged ball, said shaft bearing with said ball upon the inner surface of the ring so as to bias it elastically towards the contact making position; said throat further shaped to provide an idle path between itself and the inner circumference of the ring when the ring is held in contact position by said spring urged ball; said idle path, when the actuating mechanism is operated for breaking the circuit, allowing said shaft with its throat to be raised a certain distance without lifting the ring from its contact with the stationary contacts and to be accelerated to a velocity so as to strike with a shock movement said contact ring, whereupon, on further upward movement of the shaft, the ring is lifted and the circuit through said stationary contacts and said ring is broken.

7. Current interrupter as set forth in claim 6 wherein the contour of said throat is composed of two sectors, a lower sector, housing the spring and ball, of a radius smaller than that of the inner circumference of the ring with the center axis, when shaft and ring are in the bridging position, generally concentric with the axis of the ring, and an upper sector of the same radius as the inner circumference of the ring but with the center axis displaced between the center axis of the lower sector and the diametrically opposed side of the throat so that when the shaft holds, by means of ball and spring, the ring in its closed position, the shaft is close to but does

not contact the ring, and free space is provided between the upper sector and the inner circumference of the ring.

8. Current interrupter as set forth in claim 5 wherein the rotary contact member bridging said main contacts is a ring, a shaft being provided and supported non-revolably by said connecting members, said shaft carrying said ring freely revolvable thereabout; said shaft penetrating said ring with a throat, said throat housing a spring urged ball and bearing therewith upon the inner surface of the ring so as to bias it elastically towards the contact making position; said throat further shaped to provide said idle path between its upper surface and the upper inner circumference of the ring when the ring is held in contact position on said main contacts by said spring urged ball, said idle path allowing said throat and shaft to be raised a certain distance without lifting the ring when the actuating means are operated to break the circuit, whereupon, on further upward movement of the shaft, the ring is lifted and the circuit through said main contacts and said ring is broken.

9. Current interrupter as set forth in claim 8 wherein the rotary contact member bridging the arc horns is a roller, a shaft carrying said roller being slidably mounted in slots of said connecting members, springs being housed in said slots for urging said shaft and thereby said roller towards the contact making position of the roller between the arc horns; said slots in said connecting members being disposed relatively to said shaft and being of a length so as to allow idle motion of said actuating means together with said connecting members relatively to said shaft for a certain distance before the roller is raised out of contact with said arc horns.

10. Current interrupter as set forth in claim 9 wherein

the idle path constituted by said throat is shorter than the idle path constituted by said slots.

11. Current interrupter as set forth in claim 5 wherein the rotary contact member associated with said arc horns is a roller, a shaft carrying said roller being secured thereto and being mounted in said connecting members, said motion transmitting members for providing an idle path and interposed between said actuating means and said secondary contact bridge being constituted by slots in said connecting members, said shaft being displaceably guided within said slots, springs being housed in said slots, said springs bearing on said shaft for urging through said shaft said roller elastically towards the contacting position bridging said arc horns; said slots in said connecting members being disposed relatively to said shaft and being of a length so as to cause, on actuation of the actuating means for breaking the circuit, idle motion of said actuating means together with said connecting members relatively to said shaft for a certain distance before the roller is raised out of contact with said arc horns; thereby to delay the circuit breaking of said roller and further allow, during said idle motion, acceleration of said actuating means together with said connecting members, and, thereon, an abrupt raising of the roller from its contact with said arc horns.
